GAS BURNER ATTACHMENT

Frank H. McFall, Alliance, Ohio, assignor of one-half to Alvah L. Baker, Alliance, Ohio

Application May 12, 1934, Serial No. 725,363

3 Claims. (Cl. 158—113)

The primary object of this invention resides in the provision of an attachment for gas burners, adapted to raise the combustibility of the gas and reduce the consumption thereof to the minimum.

5 Another object of this invention resides in the provision of an attachment for gas burners of such construction that gas, upon being ejected therebeneath, will be intermingled with air and be discharged therefrom in a high state of combustibility.

10 A further object of this invention resides in the provision of an attachment for gas burners of such construction that gas will pass directly through certain orifices thereof and indirectly through certain other orifices thereof.

15 A still further object of this invention resides in the provision of an attachment for gas burners adapted to permit a greater discharge of mixed gas at certain points than at other points thereof.

20 In addition to the foregoing objects, this invention resides in an attachment for gas burners of such construction that gas ejected therebeneath will encounter baffles adapted to disintegrate the stream of gas and permit air to commingle therewith before discharging the gas, so mixed, through exit orifices.

25 Aside from the aforesaid objects this invention resides in the provision of an attachment for gas burners adapted to not only disintegrate the stream of gas ejected therebeneath, but to direct air currents into the gas, so as to create a high state of combustibility at the point of utilization.

30 With these and other objects in view, this invention resides in certain novel features of construction and arrangement of elements to be more particularly set forth in the specification, illustrated in the accompanying drawing and pointed out in the appended claims and, while the disclosure depicts my present conception of the invention, the right is reserved to make such changes in construction as come within the scope of the claims.

35 In the accompanying drawing forming a part of this application:

40 Fig. 1 is a side view of a gas burner with which is associated an attachment constructed in accordance with this invention.

45 Fig. 2 is a plan view of the attachment.

50 Fig. 3 is a bottom plan view thereof.

55 Fig. 4 is an enlarged sectional view on line 4—4 of Fig. 2.

In the present embodiment of this invention the numeral 5 designates a gas burner of the conventional type with which is associated an at-

5 tachment 10 forming the subject matter of this application.

The aforesaid attachment 10 is preferably formed of cast iron or other suitable material of concavo-convex configuration and is adapted to rest upon the burner 5 through the instrumentality of feet 12 which disposes the periphery 14 of the attachment 10 in spaced relation to the burner to provide air inlet passages 16.

10 Disposed approximately at the apex or center of the attachment is an orifice 18 while disposed adjacent the feet 12 are orifices 20 of lesser diameter than the orifice 18.

15 Surrounding each orifice 20 on three sides and extending toward the orifice 18 are baffles 22 which are of substantially U shape, the outer ends of the limbs of each baffle being connected to a part of the inner face of a foot 12, so that each orifice 20 is surrounded by four walls. These baffles are adapted to deflect gas from the burner 5 as it flows toward the orifices 20 and, through the provision of the air passages 16 between the feet 12, the stream of gas, so deflected and disintegrated, is mixed with air prior to passing through the orifices 18, 20 and other orifices 24 which are of a diameter smaller than the aforesaid orifices 20.

20 The latter orifices 24 are preferably disposed adjacent the baffles 22 in direct communication with the air passage 16 and concentrically disposed inwardly of the orifices 20 and outwardly of the orifice 18.

25 With an attachment constructed as aforesaid, it is apparent that the stream of gas ejected therebeneath will be properly disintegrated by the 30 baffles 22 whereupon air entering the passages 16 will commingle therewith and, through the provision of variable sized orifices associated with baffles arranged as set forth, the gas is not only mixed to a high state of combustibility but is 35 governed in its excursion through the orifices.

40 Having thus fully described this invention what I claim and desire to protect by Letters Patent is:

45 1. An attachment for gas burners comprising a substantially inverted saucer shaped member having legs depending from its periphery and having orifices therein, and baffles depending from its under surface, each baffle having parts connected to a leg to form an enclosure, one of certain of said orifices being within each enclosure.

50 2. An attachment for a gas burner comprising a concavo-convex member having spaced feet depending from its periphery, substantially U shaped baffles depending from the under face of 55

the member, each baffle having the ends of its limbs connected with a part of the inner face of a foot and said member having orifices therein certain of which open out into the spaces formed by the baffles and the feet, said orifices being of different sizes, a large orifice being located at the center of the member, intermediate size orifices opening out into said spaces and small orifices being located between the inner ends of the baffles.

3. An attachment for a gas burner comprising a concavo-convex member having spaced feet depending from its periphery, substantially U-shaped baffles depending from the under face of the member, each baffle having the ends of its

limbs connected with a part of the inner face of a foot and said member having orifices therein certain of which open out into the spaces formed by the baffles and the feet, said orifices being of different sizes, a large orifice being located at the center of the member, intermediate size orifices opening out into said spaces and small orifices being located between the inner ends of the baffles.
